UNITED STATES PATENT OFFICE.

JOHN WHITSON, OF NEW YORK, N. Y.

DESIGN FOR A CABINET FOR SOUND-REPRODUCING MECHANISM.

Application filed July 14, 1928. Serial No. 27,489. Term of patent 14 years.

To all whom it may concern:

Be it known that I, JOHN WHITSON, a citizen of the United States, residing in the city, county, and State of New York, have invented a new, original, and ornamental Design for Cabinet for Sound-Reproducing Mechanism, of which the following is a specification, reference being had to the accompanying drawing, forming a part thereof.

The figure is a perspective view of a cabinet for sound reproducing mechanism, showing my new design.

I claim:

The ornamental design for a cabinet for sound reproducing mechanism as shown.

JOHN WHITSON.
